Primary Examiner — Catherine Tuttle(74) *Attorney, Agent, or Firm* — Blue Filament Law PLLC; Avery N. Goldstein(57) **CLAIM**

The ornamental design for a toy, as shown and described.

DESCRIPTION

FIG. 1 is a front view of the toy showing my new design with the uppermost suction cup angled forward;

FIG. 2 is a bottom perspective view showing the toy with its uppermost suction cup angled upward and its left appendage directed upward;

FIG. 3 is a top and side perspective view showing the toy with its upper suction cup positioned as in FIG. 2 and its other appendages positioned as in FIG. 1;

FIG. 4 is the bottom plan view of FIGS. 3, 5 & 6;

FIG. 5 is the front view of FIGS. 3, 4 and 6, the opposing rear view being identical thereto; and,

FIG. 6 is the right side view of FIGS. 3-5, the opposing left side view being identical thereto.
